(57) **CLAIM**

The ornamental design for a wine glass, as shown and described.

DESCRIPTION

FIG. 1 is a perspective view of a first embodiment of a wine glass showing my new design;

FIG. 2 is a front view of FIG. 1;

FIG. 3 is a rear view of FIG. 1;

FIG. 4 is a left side view of FIG. 1; the right side view being a mirror image thereof;

FIG. 5 is a top view of FIG. 1;

FIG. 6 is a bottom view of FIG. 1;

FIG. 7 is an environmental perspective view of FIG. 1 in used with a lid;

FIG. 8 is a perspective view of a second embodiment of a wine glass;

FIG. 9 is a front view of FIG. 8;

FIG. 10 is a rear view of FIG. 8;

FIG. 11 is a left side view of FIG. 8; the right side view being a mirror image thereof; and,

FIG. 12 is a top view of FIG. 8;

FIG. 13 is a bottom view of FIG. 8; and,

FIG. 14 is an environmental perspective view of FIG. 8 in used with a lid.

The broken lines in the drawing depict environmental subject matter only and form no part of the claimed design.

1 Claim, 12 Drawing Sheets
